UNITED STATES PATENT OFFICE.

HENRI JEAN JOSEPH MARIE DE REGNAULD DE BELLESCIZE, OF TOULON, FRANCE.

WIRELESS-TELEGRAPH STATION.

Application filed August 29, 1921, Serial No. 496,532, and in France January 22, 1919.

(GRANTED UNDER THE PROVISIONS OF THE ACT OF MARCH 3, 1921, 41 STAT. L., 1313.)

This invention relates to an improved system for wireless telegraphy working on the duplex principle.

A system of the character just referred to comprises a transmitting station and several receiving stations, all these stations being arranged so as to be capable of operating simultaneously, and more particularly the aerials and the high and low frequency circuits of the receiving stations being so chosen that the operation thereof will not be disturbed by the oscillations emanating from the transmitting station which is near by. For the greater convenience of service, the apparatus serving for the transmission, and those intended for the listening to or registration of the received signals, are arranged in the same building. Up to the present, it has been customary to leave a considerable distance (about 30 km.) between the transmitting station and a receiving station pertaining to the same duplex system, so as to prevent the call-listening receiver from being disturbed or stopped by the radiation from the transmitter. Moreover, the intensity of the received signals was rather weak. Under these conditions, the most practical connection between a transmitting station and a receiving station belonging to the same system consisted in a connecting line, by means of which it was possible to actuate the transmitting station at a distance from the receiving station.

Fig. 1 is a diagrammatic showing of a known system.

Fig. 2 is the showing of a duplex system.

Fig. 3 is the showing of a system using several receivers.

Fig. 4 gives a diagrammatic explanation of the operation.

Figs. 5 to 7 show modifications of my invention.

The previously known arrangement is diagrammatically shown in Fig. 1. The switch contacts inserted in the high or low frequency circuit of the transmitting station J are actuated from the distant receiving station B by means of a key M, through the intermediation of the line F and the electro-magnet I.

In contradistinction thereto, the present invention has for its object to arrange in the transmitting station the means for the "direct" listening to or registration of the signals received at the receiving station or

stations of the same combined system. By "direct" it is understood that at the transmitting station the signals are received acoustically or registered without any supplementary transmission, as they normally are at the receiving station.

The advantages obtained by the arrangement according to the present invention are obvious. First of all it allows of the watching operators of several listening stations being concentrated in one place, all of them being capable of utilizing the transmitting station for their own purposes.

Further, the chief of the station having at his disposal several completely independent and simultaneously operating listening apparatuses, may by reason of having immediate control of the operators and of the apparatuses dispose of them according to requirements, by concentrating them either on one and the same particularly important or difficult communication or on several different communications.

Moreover, this system of connections requires a minimum of auxiliary lines for the transmission of orders.

Finally, a good solution of the transmission at a distance of the acoustically received signals leads to the contemplation of a supplementary concentration in a central office independent of the wireless stations of all the signals received at the different receiving stations of a country or of a portion thereof.

The transmission of the undulatory currents constituting the signals to be received or registered, from the receiving station to the transmitting station, and if desired from the receiving station to an independent central office of the system, is effected by means of the lines F_1 , F_2 (Fig. 3). One of the extremities of each line is suitably connected, as hereinafter more particularly referred to, to the proper receiving apparatus, the purpose of which is to transform the Hertzian waves into oscillations capable of being read or registered; the other extremity thereof is connected to the telephone or registering apparatus of the transmitting station or of the central office.

Fig. 2 shows the principle of the grouping of the stations and apparatus of a duplex system. A is the transmitting station, and B the receiving station. The station B mainly comprises an open or closed receiv-

ing aerial D, actuating the group E of tuning circuits, amplifiers, detectors, etc., constituting the ordinary receiving apparatus.

At the outer end of the group E, there is provided a telephone T in order that supervising operator may tune the receiving apparatus, and an arrangement K herein-after more particularly referred to serving to connect the receiving station to the connecting line F₁ which consists of two conductors having substantially the same electrical constants, that is, resistance, inductance and capacity. The other end of the line F₁ reaches the transmitting station, where it actuates the telephones or registering apparatus G₁ which are employed, the latter being placed not far from the transmitting key M.

It is to be understood that several receiving stations B, B' (Fig. 3) may be placed in proximity to the transmitting station A, and that they may supply not only the transmitting station A of the duplex system through lines F₁ and F'₁ respectively, but that they may also supply a central office C, common to the stations B and B' and to the other stations, which are more or less distant. This general arrangement is shown in Fig. 3.

In order to ensure the good working of such an installation, a certain number of conditions must be fulfilled.

(a) The problem is evidently easier to solve when the received signals are more intense, and the distance over which they are transmitted by wire is smaller.

These two conditions are obtained simultaneously by arranging the duplex system according to one of the methods described in applicant's co-pending application for Letters Patent, Serial No. 318,368, filed Aug. 18, 1918. These arrangements permit of imparting to the call-listening receiver a considerable sensitiveness and, consequently, greatly increasing the intensity of the received signals without such signals being in any way disturbed by the transmission from the station A which may be only a few thousand, or even a few hundred, metres distant.

From this point of view the problem is completely solved.

(b) The electric constants of the lines F₁ . . . of the listening or registering apparatus G₁ . . . , of the connection K and of the proper receiving apparatus E must be adapted so as to suitably correspond to each other. This may be accomplished in accordance with known principles, as long as the distance A—B is not greater than 2 or 3 km. The apparatus, telephones, amplifiers, transformers, etc., of any standard model employed in wireless telegraphy may be employed. These principles are so well known to engineers working in the arts of tele-

graphy and telephony that no explanation of them is required in order to enable those skilled in such arts to practice applicant's invention. It may be mentioned, however, that in accordance with one of these principles, the impedance of the instrumentalities at each end of the line F₁ should be substantially equal to the surge impedance of the line. In other words, if the surge impedance of the line F₁ were 500 ohms, the impedance of the device G₁ at the station A should be substantially equal to 500 ohms, and the aggregate impedance of the devices K, T and E at the station B should also be substantially equal to 500 ohms. The basis of this principle is the prevention of reflection of energy along the line F₁.

(c) The presence of the lines F₁ . . . ending at the receiving station B should not interfere with the duplex service. However, the more or less energetic action of the transmitting apparatus A upon these lines will produce therein a certain number of forced oscillations, so that there is the risk that the wires will transmit the disturbing effect of the transmitting apparatus as far as the interior of the receiving room. If this danger is not met by great precaution, all the improvements incorporated in the construction of the proper receiving apparatus will be rendered useless, and the duplex working made impossible.

It is first to be noted that the action of the transmitting aerial on a line F may be analyzed as follows: (see Fig. 4).

It produces an electromotive force of circulation X, shown by the arrows in full lines in Fig. 4 and two equal electromotive forces YY of the same direction (arrows in dotted lines) acting upon the two wires of the line considered as an open aerial.

The amplitude of X and YY may be attenuated by burying the line F₁ on part of its course. The subterranean part must not, however, exceed a certain length, otherwise the intensity of the signals would be too much weakened. For this reason, only the two ends of the line over a distance of a few hundred metres are buried. By this simple measure, the following advantages are attained:—The aerial part of the line F₁ is removed from the transmitting station, and the more powerful high frequency oscillations are almost entirely absorbed in the ground, before their arrival at the receiving station. This arrangement is much more efficient than the placing in parallel between the ground and the wires of the line of two large non-distributed capacities.

A further attenuation of the force X may be obtained by a counter-induction arrangement of the aerial part of the line, that is to say by crossing from distance to distance the two wires so as to annul the total enclosed flux. By judiciously using this precaution,

X may be rendered negligible. The remaining disturbance could then be due only to the components Y.

Consequently, what remains to be done, is to find a means of coupling K between the wires F₁ and the receiving box, such that the disturbances due to Y shall not be transmitted to the receiving apparatus. This may be accomplished in various ways, and among numerous solutions the following three may be mentioned, by way of example.

In Fig. 5, the coupling is effected by a transformer or a system of transformers PQ. The winding Q, which acts as primary relatively to the disturbances coming from the line F₁, is earthed at a suitable point. By this means a great reduction in the average potential of this winding is obtained, which attenuates the effect due to the electrostatic coupling between P and Q.

As to the induction effect produced on the winding P by the leakage currents i_a , i_b due to the forces Y and flowing to the ground, it may evidently be nil if the earthing point is properly chosen.

In Fig. 6, the connection is effected by an acoustic coupling. The undulating current constituting the signal to be read or registered actuates a vibrating membrane Q through the intermediation of an electromagnet P, which may or may not be polarized. The said membrane actuates in its turn a microphone S, placed at the end of the connecting line F. Usually, the receiving apparatus adapted to work on the duplex system is enclosed in a Faraday cage which protects the very sensitive parts of the apparatus, such as the amplifier, against the direct action of the adjacent transmitting station. The continuous wall of this cage is replaced in the part lying between the plates Q and S by a wire gauze R with rather small mesh, which does not stop the acoustic transmission, but acts against any electrostatic effect between the line F₁ and the receiving apparatus.

Fig. 7 illustrates an electro-mechanical coupling in which the vibrating plate S of the microphone is directly actuated by the electro-magnet P. The gauze R may be replaced in this arrangement by a very thin sheet of non-magnetic metal.

It will be obvious that in all these arrangements, an amplifying relay of any suitable character may be inserted on the line F.

Having described my invention, what I claim is:

1. In a duplex wireless system, composed of a transmitting station and a receiving station having receiving apparatus intended to work simultaneously with the transmitting apparatus, means at said transmitting sta-

tion for indicating the received signals, a connecting line between said indicating means and the receiving apparatus of the receiving station, and means located at said receiving apparatus for decreasing the disturbing effect on said apparatus of currents in the connecting line originating from the transmission station on the one hand and passing the received signal effects to the connecting line on the other hand, said last mentioned means consisting of a ground in the circuit of the connecting line.

2. In a duplex wireless system, composed of a transmitting station and a receiving station having receiving apparatus intended to work simultaneously with the transmitting apparatus, means at said transmitting station for indicating the received signals and a connecting line between said indicating means and the receiving apparatus of the receiving station said connecting line being coupled to the receiving apparatus through a coil grounded at an intermediate point.

3. In a duplex wireless system, composed of a transmitting station and a receiving station having receiving apparatus intended to work simultaneously with the transmitting apparatus, means at said transmitting station for indicating the received signals, and a connecting line between said indicating means and the receiving apparatus of the receiving station, said connecting line being crossed at intervals for decreasing the effect of said transmitting station on the receiving apparatus.

4. In a duplex wireless system a transmitting station and a receiving station adapted to work simultaneously, means at said transmitting station for indicating received signals connecting lines for joining the indicating means with said receiving station, said connecting lines being crossed at intervals and having a substantial portion adjacent the transmitting station buried in the earth and means for coupling said connecting lines to said receiving station comprising a coil grounded intermediate its ends.

5. In a duplex wireless system a transmitting station and a receiving station adapted to work simultaneously, means at said transmitting station for indicating received signals, connecting lines for joining the indicating means with said receiving station, said connecting lines being crossed at intervals and means for coupling said connecting lines to said receiving station comprising a coil grounded intermediate its ends.
